UNITED STATES PATENT OFFICE.

PETER SCHWEHM, OF REISHOLZ, GERMANY.

GAS-ENGINE.

No. 806,199.

Specification of Letters Patent.

Patented Dec. 5, 1905.

Application filed December 31, 1902. Serial No. 137,873.

To all whom it may concern.

Be it known that I, PETER SCHWEHM, a citizen of Germany, residing at Reisholz, near Düsseldorf, Germany, have invented new and useful Improvements in Gas-Engines, of which the following is a specification.

This invention relates to a gas-engine of improved construction, and more particularly to the means for controlling the flow of gas and air to the cylinder.

The subject of the present invention, a two-cycle gas-engine, is illustrated in Figures 1 and 2 of the accompanying drawings in section.

The cylinder 11 of the gas-engine receives the necessary explosive mixture of gas and air from a gas-pump 7 and an air-pump 8, which may be operated and regulated independently of the gas-engine. Into the conduits 6 and 6^a, which connect the pumps 7 and 8 to the cylinder 11, pressure-chambers 9 and 10 are inserted in order to regulate and equalize the pressure of the gas and air, respectively. In works in which there are several gas-engines common gas and air pumps and intermediate reservoirs can be employed.

From the chambers 9 and 10 the gas and the air, respectively, enter the cylinder 11 of the gas-engine by means of valves which are operated independently of each other, so that an exact regulation of the engine may be effected. In order to expel the gas residue after the explosion, the cleaning-air admitted through the common inlet-valve 2 must in order to retain its form of a strong properly-conducted column of air be kept together after entering and conducted centrally, or nearly so, into the working cylinder 11, through the valve and the compression-chamber 4, in the direction of the axis of the cylinder. So, also, the velocity of the particles of air must be fairly equal, so that the movement of the whole column is a steady and driving one and that the cleaning-air and the remainder of the mixture are prevented from mixing. As the mixture is also employed for displacing the residue from the cylinder, its movement must also answer the before-mentioned requirements. In the present construction the method of conducting the air uniformly is as follows: The valve 1, which controls the admission of gas to the mixing-chamber, is provided with a hollow stem 20, engaged by an elbow-lever 21. This lever receives motion from regulator-spindle 22 by means of cam 23 and link 24. The in-

let-valve 2 has a stem 25, which is embraced by hollow stem 20 and receives motion from spindle 22 by cam 26, link 27, and elbow-lever 28. Both valves 1 and 2 are provided with conical caps 3 in order to evenly conduct the gas and the gas-and-air mixture to the explosion-chamber 4. The compression-chamber 4 is elbow-shaped and tapers gradually behind the inlet-valve, whereby the cross-section of the passage is reduced to the desired measurement, rendering the way taken by the air-current as even as possible. Before entering the cylinder and after being axially directed the cross-section of the passage gradually widens conically. To conduct the displaced residue gradually and uniformly to the exit-openings 5, the piston is furnished with a conical cap 12, leading with a convex curve to the exit-openings 5 in a direction perpendicular to the axis of the cylinder. Similarly the piston-rod nut and collar 12^a are conically formed. As the cleaning-air is introduced through the same inlet-valve as the mixture, the space between the gas-valve and the inlet-valve must be as small as possible, so that the quantity of ready mixture which could eventually be carried away by the passage of the cleaning-air be kept at a minimum. For this reason the gas-valve 1 is mounted centrally immediately behind the inlet-valve 2. By this central arrangement of the two valves I attain at the same time a thorough mixing of the gas and air. The valve-caps 3 above-mentioned serve to limit the storing-chambers or reservoirs formed around the valves 1 and 2. In order to insure the small quantity of mixture between the gas-valve and the inlet-valve being utilized, the gas-valve (which is worked independently) is closed a short time before the inlet-valve is closed, so that the still-entering air presses the gas out of the space between the two valves into the compression-chamber 4.

The engine is regulated either by variably opening the inlet-valve or by throttle, clack, or slide valves 13 and 14, arranged within the conduits 6 6^a near the inlet-valve, in combination with a return-pipe 15, having a valve 16, which is opened by an excess of pressure in the intermediary chamber 9. If the engine is to be regulated by constant mixture, throttle and return-pipe are necessary for gas and air pump. If regulated by variable mixture, they are necessary only for the gas-pump 7.

The return-pipe can act by leading the surplus turned out by the pump, which is always working full, back into the suction-pipe or by creating circulation in the pumps to diminish the quantity turned out. For the latter purpose pipe 6 communicates with a cylinder 30, containing a spring-influenced piston 31. The piston-rod 32 is by bell-crank lever 33 and a rod 34 connected to two clack-valves 35 36. These valves play in a duct 37, that connects the ends of cylinder 7 at opposite sides of the piston. If the gas-pressure in pipe 6 and chamber 9 is excessive, the piston 31 is forced outward against the action of its spring in order to open valves 35 36 by lever 33 and rod 34. After the valves have been opened the gas entering the pressure side of cylinder 7 will be conveyed to the suction side of the same, so that the pressure within chamber 9 and pipe 6 will decrease until the valves 35 36 are again closed.

What I claim is—

1. In a gas-engine, the combination of a gas-pump and an air-pump with a gas-pipe 25 and an air-pipe, a common mixing-chamber,

a valve between the gas-pipe and mixing-chamber, a cylinder and piston, a valve between the mixing-chamber and cylinder, a regulator-spindle, means intermediate said spindle and the valves for operating the 30 valves independently of each other, and means independent of the piston for operating the gas and air pumps, substantially as specified.

2. In a gas-engine, the combination of a 35 gas-pipe and an air-pipe with a common mixing-chamber, a valve controlling the gas-pipe, a second valve controlling the mixing-chamber, a cylinder having an elbow-shaped and flaring end which constitutes a compression-chamber, and a piston having a coniform head adapted to be projected into said chamber, substantially as specified. 40

Signed by me at Düsseldorf, Germany, this 16th day of December, 1902.
